UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, A CORPORATION OF DELAWARE.

DESIGN FOR AN AUTOMOBILE RADIATOR CASING.

Application filed February 7, 1924. Serial No. 8,562. Term of patent 14 years.

To all whom it may concern:

Be it known that I, JOSEPH H. BOURGON, a subject of George V, King of Great Britain and Ireland, and resident of Detroit, in the county of Wayne and State of Michigan, have invented a new, original, and ornamental Design for an Automobile Radiator Casing, of which the following is a specification, reference being had to the accompanying drawings, forming a part thereof.

In the drawings,

Fig. 1 is a front elevation of an automobile radiator casing showing my new design, Fig. 2 is a side elevation of the radiator casing shown in Fig. 1, Fig. 3 is a front perspective view of the radiator casing and Fig. 4 top plan view.

I claim:—

The ornamental design for an automobile radiator casing as shown.

Signed by me at Detroit, Michigan, this 29th day of Jan., 1924.

JOSEPH H. BOURGON.
